UNITED STATES PATENT OFFICE.

CHARLES F. PORTER, OF NEW YORK, N. Y.; SARAH HARRIETT PORTER, EXECUTRIX OF SAID CHARLES F. PORTER, DECEASED, ASSIGNOR TO SARAH H. CRAWFORD, OF CHICAGO, ILLINOIS.

HAIRDRESSING DEVICE.

Application filed March 22, 1921. Serial No. 454,362.

To all whom it may concern:

Be it known that I, CHARLES F. PORTER, a citizen of the United States, and a resident of New York city, in the county of New York and State of New York, have invented certain new and useful Improvements in Hairdressing Devices, of which the following is a specification.

My invention relates to devices for dressing hair and particularly to that class of devices adapted for imparting a wave or undulation to a strand of hair.

In order to impart a wave to a strand of hair it is necessary that the strand of hair be given the desired contour and be maintained in such condition until the contour is more or less permanent either by reason of the length of time during which it is retained in the desired arrangement or by the application of heat.

Heretofore, a wave or curl has been imparted to a strand of hair by wrapping it upon a base member and holding it thereon by means of an elastic band, but such elastic bands deteriorate, break under the tension required and become entangled in the hair. The rubber of such elastic bands also has a harmful effect on the gray hair.

It is an object of my invention to provide a device for waving or curling a strand of hair which is simple and durable and will not become entangled in the hair or exert a harmful effect thereupon and which will not deteriorate.

Another object of my invention is to provide means for waving or curling a strand of hair which will firmly clasp and retain the strand in the desired and necessary arrangement and which will be simple but effective in its application and removal.

Other and further objects and advantages of my invention appear from the following description taken in connection with the accompanying drawings forming a part of this specification and will be pointed out in the hereunto appended claims.

In the drawings in which like reference characters refer to similar parts:

Fig. 1 is a perspective view of the device embodying my invention showing one manner of wrapping a strand of hair thereupon;

Figs. 2, 3 and 4 are detailed views.

In the drawings which illustrate one form of my invention for the purpose of disclos-

ing the same, a waving member 1 shown in detail in Figs. 2 and 3 is adapted to have wrapped upon it a strand of hair 6 for imparting thereto the desired curl or wave. To make a uniform wave the member 1 should be uniform throughout its length and of a circular, elliptical, oval or other rounded cross section, it being substantially a length of a rod having such a shape. The hair may be wrapped in any well known manner to secure the desired effect, the manner of wrapping the hair forming no part of my invention. An embracing or retaining member 2 is provided for firmly holding the hair wrapped upon the base member 1. The embracing member 2 is connected to the base member 1 so as to be readily detachable therefrom. The embracing member 2 is resilient and preferably includes a curved portion, the resiliency operating to draw the ends towards each other. 55

The means whereby the embracing member and the base member are connected is rendered effective by the resiliency of the embracing member 2. In the embodiment of my invention herein described the connecting means comprises a slot 3 in the end of the base member 1 through which the embracing member 2 or an off-set portion 4 thereof extends. The embracing member 70

provided preferably at its ends with retaining portions 5 so that the portions of the embracing member which extend through the slots and are held therein by the resiliency of an embracing member will be retained within the slots against the pressure 75 existing between the strand of hair 6 and the embracing member 2. When the resilient retaining member 2 is a small wire, as shown in the drawings, the sharp ends unprotected would be injurious to the wearer.

Thus the portions 5 perform a double function. The resiliency of the embracing member 2 permits the off-set portions 4 to be spread apart so that there may be readily positioned within and removed from the slots 3 and this resilience also exerts pressure on the strand of hair 6 so as to hold it in place and impart to it the desired wave or curl. 80

It will be apparent from the above description that a hair dressing device embodying my invention is simple, durable, effective and readily operative. 100

105

While I have described and shown specific details of the construction of my invention, it is to be understood that I am not limited thereto but that my invention is described by the hereunto appended claims.

What I claim as new and desire to secure by Letters Patent is:—

1. In a device of the class described, a member adapted to have a strand of hair wrapped upon it and having notches in its ends, and normally curved a resilient hair embracing member extending through a notch in each end of said first named member and having retaining parts at its ends, said embracing member being held in said notches by its resilience.
2. In a device of the class described, a member adapted to have a strand of hair wrapped upon it and having notches in its ends, and a resilient hair embracing part having a curve therein and extending through said notches in the ends of said first member and provided at its ends with retaining parts.
3. In a hair waver a member adapted to have a strand of hair wrapped upon it and having notches across its ends, and a hair retaining member of resilient metal and comprising a normally curved hair engaging portion and integral end portions substantially at right angles to said hair engaging portions and adapted to fit in said notches and to be held therein by the resilience of said hair engaging portion, said end portions having retaining parts at their extremities to prevent them from sliding through said notches.
4. In a device of the class described, a member adapted to have a strand of hair wrapped upon it and having notches in its

ends, and a resilient hair retaining member extending through and beyond a notch in each end of said first named member and having retaining parts on its ends.

5. A hair waver having, in combination, a hair waving member and a hair retaining element, the waving member having the form of a rod of rounded cross section and having transverse notches in the ends thereof, the retaining element being a length having resilient material therein, said length having its major portion spanning substantially the length of the waving member, and having its ends pass substantially at right angles to the major portion through and beyond the notches, wherein they are held by the resiliency of the retaining element and enlargements on said ends to retain said ends in the notches.

6. A hair waver having, in combination, a waving member and a hair retaining element, the waving member having the form of a rod of rounded cross section and having an end with a transverse notch therein, the retaining element being a length having resilient material therein and having its major portion adapted to span substantially the length of the waving member, said element having one end substantially at right angles to the major portion, said end being adapted to pass through and beyond the notch wherein it is held by the resiliency of the element, an enlargement on said end beyond the notch and means to hold the opposite end of the element resiliently to the corresponding end of the waving member.

In testimony whereof, I have signed my name to this specification.

CHARLES F. PORTER.

Certificate of Correction.

It is hereby certified that the assignee in Letters Patent No. 1,565,588, granted December 15, 1925, upon the application of Charles F. Porter, of New York, N. Y. (Sarah Harriett Porter executrix of said Charles F. Porter, deceased), for an improvement in "Hairdressing Devices," was erroneously described and specified as "Sarah H. Crawford," whereas said assignee should have been described and specified as *Sarah H. Porter*, as shown by the records of assignments in this office; page 2, line 73, claim 6, after the word "notch" insert a comma; and that the said Letters Patent should be read with these corrections therein that the same may conform to the record of the case in the Patent Office.

Signed and sealed this 22d day of June, A. D. 1926.

[SEAL.]

* M. J. MOORE,
Acting Commissioner of Patents.
